CLOSURE FOR HOPPER OF HOPPER TYPE
RAILWAY CARSGeorge B. Dorey, Westmount, Quebec, Canada,
assignor to Enterprise Railway Equipment
Company, Chicago, Ill., a corporation of Illinois

Application November 18, 1949, Serial No. 128,210

2 Claims. (Cl. 105—305)

1

This invention relates, generally, to sliding closures for the discharge opening of a hopper of a hopper type railway car, and it has particular relation to operating and locking means therefor. The improvement is especially concerned with sliding gates for closing the opening of hopper cars and is of special importance in connection with gates which necessitate the exercise of considerable force to initiate their opening movement. This is particularly true with a hopper positioned above the rails and at a substantial distance inwardly of the car side wall thereby necessitating the operation of the gate from a location outwardly of the car side wall.

The conventional method of operation now widely used involves a horizontally disposed and transversely extending operating shaft with cooperating rack and pinion means and an operating head for receiving an operating bar so that the shaft can be rotated from a position adjacent one side of the car. In such a construction there is a tendency for the car side wall to interfere with the free movement of the operating bar since it swings in substantially a vertical plane. According to this invention a construction is provided wherein the shaft and pinion means are positioned so as to operate about a vertical axis. This permits of operation by a bar which can be swung substantially in a horizontal plane.

Among the objects of this invention are: To provide a construction which will permit operation of a sliding gate by a bar operating in a plane substantially parallel to the plane of movement of the gate; to provide a construction involving a gate carrying frame of simplified construction; and to provide an improved latching and sealing device for the gate in closed position.

Other objects of this invention will, in part, be obvious and in part appear hereinafter.

This invention is disclosed in the embodiment thereof shown in the accompanying drawings and it comprises the features of construction, combination of elements and arrangement of parts which will be exemplified in the construction hereinafter set forth and the scope of the application of which will be indicated in the appended claims.

For a more complete understanding of the nature and scope of this invention, reference can be had to the following detailed description, taken together with the accompanying drawings, in which:

Figure 1 is a top plan view of a pair of hopper

2

frames in the form of outlet castings together with cooperating horizontally slideable gates;

Figure 2 is a view, partly in side elevation and partly in section, showing the application of the present invention to a pair of adjacent hoppers; and

Figure 3 is a detail sectional view, taken, generally, along the line 3—3 of Figure 2.

The present invention is illustrated as applied to a conventional hopper type railway car having a hopper with a discharge opening located in the space above and between the rails, one of which is indicated at 10 in Figure 3. As there shown the reference character 11 indicates a center sill of the car and the reference character 12 designates one side wall thereof. Four-sided hoppers, indicated generally at 13, are located between the center sill 11 and the car side wall 12. As shown more clearly in Figure 2 the hoppers 13 are located in pairs and the present invention is applied thereto although it will be understood that it may be employed in connection with a single hopper only. Each hopper 13 is formed by walls 14 and 15 which extend transversely of the car and are joined by inner and outer walls 16 and 17. The inner wall 16, Figure 3, is indented as indicated at 18 to accommodate a bottom flange 19 of the center sill 11.

The walls 14, 15, 16 and 17 at their lower edges define a discharge opening which is surrounded by an outlet frame casting that is indicated, generally, at 22. It may be held in position by rivets 23 as shown. The outlet frame casting 22 includes frame end walls 24 and 25 which are coextensive with the lower portions of the walls 14 and 15 respectively. Also it includes inner and outer frame side walls 26 and 27 which are coextensive with the lower portions of the inner and outer walls 16 and 17 respectively. At the lower end of the outlet frame casting 22 there is a four-sided chute which is formed by depending end walls 28 and 29 and depending side walls 30 and 31. Flanges 32 and 33 extend outwardly from the walls 28 and 31 respectively for receiving and clamping to a separate chute (not shown). Flanges from this separate chute are arranged to interfit with slots 34 and 35 as will be understood readily.

As illustrated more clearly in Figure 2 the end wall 29 has a transverse slot 37 through which a gate 38 can move for closing off the discharge opening at the bottom of each of the hoppers 13. The end wall 29 has a ledge 39 along its upper edge which defines the lower side of the transverse slot 37 and serves to support the gate 38

in its sliding movement to and from the closed position. The ledge 39 in combination with the lower portion of the end wall 29 which includes the U-shaped slot 35 provides a relatively strong beam structure which extends transversely across and underneath the gate 38. The forward end of the gate 38 rests on a shelf 40 which extends horizontally of the end wall 28.

The gate 38 is of plate-like construction and it is arranged to be supported and slide on runways 42 and 43 which are provided at the upper edges of the side walls 30 and 31. The runways 42 and 43 and their relationship to the gate 38 of each frame casting 22 are shown more clearly in Figure 1 of the drawings. Projections 44 and 45 extend inwardly from the side walls 26 and 27 of the frame casting 22 over the upper surface of the gate 38 along the margins thereof to prevent the same from bouncing upwardly when the hoppers 13 are empty.

With a view to supporting the gates 38 in the open positions, L-shaped extension rails 46 and 47 are provided. They are attached by suitable means, such as rivets, at their ends to ears 48 and 49 which are formed integrally with the side walls 30 and 31 of the outlet frame casting 22 associated with each of the hoppers 13. Guide lugs 50, Figure 3, are formed integrally on the under side of each of the gates 38 for maintaining it in proper spaced relationship between the extension rails 46 and 47 and guiding it in its movement therealong.

In accordance with the present invention, provision is made for moving each of the gates 38 to open and closed position by employing a pinion 51 which is centrally rotatably mounted thereon so that it can be rotated about a vertical axis. Each pinion 51 is supported for operation by a bifurcated bracket that is indicated, generally, at 52 and formed integrally with each gate 38. The bracket 52 includes an arm 53 which is positioned well below the under surface of the gate 38 and an extension 54 which projects from the main portion of the gate 38 as shown more clearly in Figure 2. The arm 53 and extension 54 provide bearings for rotatably mounting a shaft 55 which has a non-circular portion intermediate its ends coextensive with the pinion 51 so that the same is non-rotatably mounted thereon. At its upper end the shaft 55 has a head, shown generally at 56, which is provided with transversely extending slots 57 for receiving an operating bar to be described. A rivet 58 extends through the shaft 55 and through a washer 59 below the arm 53. It is headed over as shown so as to hold the parts inseparable.

The teeth of the pinion 51 extend vertically and are arranged to mesh with the vertical teeth of a rack 60. It will be observed that a rack 60 is provided for each pinion 51 and that the racks 60 are mounted underneath the hopper walls 15 on a support 61 in the form of an angle. The support 61 is secured at its ends by rivets to bracket walls 62 which are cast integrally with the end walls 29 of each of the outlet frame castings 22. Gusset walls 63, also cast integrally, serve to brace the bracket walls 62 laterally.

As indicated, the slotted head 56 is arranged to receive an operating bar for rotating the pinion 51. In Figure 3 of the drawings an operating bar 64 is indicated by broken lines as being positioned in one of the two slots 57 in the head 56. It will be appreciated that the operating bar 64 is swung substantially in a horizontal plane parallel to the gate 38 for rotating the pinion 51 and

moving the corresponding gate 38 toward the open or closed position depending upon the direction in which the bar 64 is moved. Since the slots 57 are open at their upper ends, the operating bar 64 cannot be accidentally left in place. Once the operator lets go his grasp on the end of the bar 64, it will fall under the influence of gravity to the ground. The outward movement of each of the gates 38 to the open position is limited by a stop 65 which projects upwardly from and is formed integrally with each of the racks 60.

The disposition of the teeth of the rack 60 vertically and a corresponding disposition of the teeth of the pinion 51 are advantageous inasmuch as there is little tendency for grit or foreign matter to be retained thereby and interfere with proper operation. Also it will be noted that each pinion 51 is well protected beneath its gate 38 and is well supported by the bifurcated bracket construction 52. An important advantage of the present invention as disclosed herein resides in the absence of parts projecting below the outlet frame casting 22 and the complete accessibility of the various parts. Another important advantage is the possibility of obtaining substantially unlimited leverage for rotating the pinion 51 since the operating bar 64 is arranged to swing in substantially a horizontal plane and thus it does not interfere with the side wall 12.

In accordance with this invention provision is made for latching each of the gates 38 in the closed position. This is accomplished by casting an ear 66 with each of the outlet frame castings 22 as an extension of the outer side wall 27. This is shown more clearly in Figure 2. The ear 66 has a key-shaped opening 67 for receiving a key-shaped head 68 of a bolt 69, Figure 1. The bolt 69 is slidably and rockably mounted between projections 70 which are cast integrally with each of the gates 38 and extend upwardly therefrom. Each bolt 69 is held in place between the projections 70 by plates 71 which are welded thereto. A handle 72 extends radially from the body of the bolt 69 between the pairs of projections 71 and it is positioned so as to bias the key-shaped head 68 out of registry with the key-shaped opening 67 in the ear 66. A slot 73 may be located in the key-shaped head 68 for receiving a seal in accordance with conventional practice.

The functioning of the present invention will be understood readily from the foregoing description and by reference to the drawings. Assuming that the bolt 69 is withdrawn from engagement with its key-shaped opening 67 for one of the gates 38, the operator then places the operating bar 64 in the transversely extending slots in the head 56 and rotates the same in the proper direction to move the gate 38 on which the selected head 56 is mounted to the open position. The operating bar 64 then is swung as far as space limitations will permit. Thereafter it is removed from the head 56 and placed in the next slot for continuing the opening movement of the gate 38. The gate 38 is closed by reversing this sequence of operations.

Since certain further changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. In combination, a hopper for a railway car

having inclined sides defining a hopper opening spaced inwardly from a side wall of the car, a frame around said opening, a gate carried by said frame for closing said opening, said gate being horizontally slidably from and to closed position on said frame underneath one of the inclined sides of said hopper, a pinion centrally mounted along one end of and below said gate for rotation about a vertical axis, a rack carried by said frame below said gate and extending endwise therefrom and engaged by said pinion, and a head fastened to and rotatable coaxially with said pinion and disposed above said gate and having a pair of U-shaped angularly related slots therein for receiving in either of them a horizontally positioned removable operating bar insertable from one side of the car to rotate the pinion associated therewith in engagement with its rack to move said gate from and to the closed position by successively positioning said bar in said slots and swinging the same through an arc.

2. In combination, a pair of hoppers for a railway car having inclined sides defining a hopper opening spaced inwardly from the side wall of the car, adjacent sides of said hoppers defining an inverted V-shape, a frame around each hopper opening, a gate carried by each frame for closing the corresponding hopper opening, extension rails between said frames for supporting said gates in their movement from and to open position, each gate being horizontally slidable from and to closed position underneath the side

20

25

30

of its hopper forming said inverted V-shape, a pinion centrally mounted along one end of and below each gate for rotation about a vertical axis, a support carried by and extending between said frames below said gates, a pair of racks carried by said support and extending endwise from the respective gates in closed position and engaged by the respective pinions carried thereby, and a head fastened to and rotatable coaxially with each pinion and disposed above the respective gate and having a pair of U-shaped angularly related slots therein for receiving in either of them a horizontally positioned removable operating bar insertable from one side of the car to rotate the pinion associated therewith in engagement with its rack to move the corresponding gate from and to the closed position by successively positioning said bar in said slots and swinging the same through an arc.

GEORGE B. DOREY.
